RAIL ANCHOR

Application filed June 13, 1929. Serial No. 370,607.

My invention relates to rail anchors adapted to grip the base portion of a railroad rail and engage a stationary part of the roadbed to resist longitudinal creeping movements of the rail.

A principal object of the invention is to provide an improved rail anchor of the above general character which will be sufficiently resilient to permit it to be readily applied and removed from the rail when desired, and which will grip the rail by both resilient and positive gripping forces to resist longitudinal movement of the rail when the anchor is in its normally applied position.

Another object is to provide a rail anchor having a depending tie abutment which is relatively resilient transversely of the rail so as to permit the anchor to be readily sprung over the opposite edges of the rail base, but which is relatively rigid longitudinally of the rail so as to provide a positive and non-yielding grip on the rail base when the abutment is pressed against an adjacent cross-tie.

A further object is to provide a one-piece anchor adapted to exert, either singly or in combination with other gripping forces, a grip on the top and bottom surfaces of one base flange of the rail, which grip normally results from pressure of the tie abutment against the adjacent cross tie, tending to tilt the anchor about a horizontal axis extending transversely of the rail, and to provide, in this connection, a relatively long bottom bearing which is so formed with relation to the tie abutment, as to provide a brace for resisting excessive tilting of the anchor and which at the same time will provide a convenient face for receiving the hammer blows or other application of force, to spring the anchor transversely of the rail to its applied position.

Further objects will appear from the detailed description of the various features of construction shown in the embodiments illustrated, together with the apparent or the expressed purposes and advantages of the various constructions described.

In the drawing:

Fig. 1 is a plan view of the base portion of a railroad rail and a fragmentary portion of a cross-tie showing a rail anchor device, constructed in accordance with my invention, applied in its normal operative position on the base portion of the rail.

Fig. 2 is a front view of the construction shown in Fig. 1 and illustrating in dotted lines one position assumed by the anchor during its applying movement.

Fig. 3 is an end view of the anchor illustrating the manner in which the under rail bearing and tie abutment serve as a brace during the presence of a tilting force on the anchor.

Referring to the drawing wherein I have illustrated one preferred embodiment of my invention, 10 designates the railroad rail and 11 one of the cross-ties on which the rail is supported. The embodiment illustrated in the drawing is preferably in the form of a one-piece device and consists of a body portion 12 formed at one end with means, preferably a jaw 13, for engagement with one flange of the base portion of the rail. The portion 13 preferably bears against the top inclined surface of the base flange engaged and is connected with a vertically disposed portion 14 of a depending loop 15. The upper portion of the vertical member 14 bears against a vertical edge portion of the base flange. The loop 15 extends downwardly a substantial distance below the bottom surface of the rail base so as to provide a relatively large tie abutment. Connected with the vertically extending portion 14 is a horizontal portion 16 of the loop, the latter of which connects with an upstanding angularly disposed portion 17. The portion 17 preferably diverges from the vertical face of the cross-tie 11 backwardly from the tie and also converges upwardly toward the vertically disposed portion 14 of the loop. It will be seen, therefore, that the portion 17 extends upwardly and backwardly from the adjacent tie and extends also at an angle toward the outer edge of the adjacent flange of the rail base (shown best in Figs. 2 and 3). The loop portion is

preferably relatively narrow transversely of

the rail so as not to be flexed or distorted by being pressed downwardly into the ballast of the road-bed, but which at the same time will be relatively resilient transversely of the rail. The upper end of the portion 17 is connected to the body 12 by means of a bearing portion 18 which extends longitudinally of the rail. The jaw 13, members 14 and 19 are preferably disposed in the same vertical plane. The bearing portion 18 extending backwardly from the ties provides a relatively long bearing surface 18a, which resists excessive tilting of the jaw end of the anchor when the tie abutting loop is pressed against the tie. The end of the body 12 opposite the jaw 13 is provided with a jaw 19 which engages the opposite edge of the rail base. Preferably the jaw 19 is inturned so as to extend over the upper edge of the base flange and thereby insures against any distortion of the anchor, such, for example, as may result from the tilting action, from disengaging the locking end 19 from the rail.

25 In the drawing I have shown my preferred embodiment formed from a metal bar round in cross-section. While the relatively large bearing surface, provided by the angular portion 18, makes it practicable 30 to form an anchor of this character from round stock, and at the same time avoids excessive tilting action, it should be understood that I do not wish to limit this invention to the use of the round stock.

35 In applying the anchor to a rail, the jaw end 13 is first hooked over one base flange of the rail in a manner indicated in dotted lines in Fig. 2. Pressure is then applied to the striking face 20 to spring the loop 40 transversely of the rail and cause the jaw 19 to engage over the opposite edge of the rail base.

During the initial applying movement, the lower corner 21 of the rail base enters in 45 the space 22 between the members 14 and 17 of the spring loop. The transverse flexing of the member 17 of the loop, in addition to exerting a transverse flexing of the loop, produces also a vertical spring grip between 50 the lower portion of jaw 13 and the bearing 18a. The latter grip is effected by the tendency which the transverse flexing has to move the portion 17 of the loop to the perpendicular. Hence when the anchor is applied, there is a grip exerted on opposite 55 edges of the rail, resulting from the tendency which the loop has to return to the position from which it was sprung. There is also a vertical grip between the lower surface 60 of the jaw 13 and the bottom bearing surface 18a, resulting from the transverse movement of the portion 17 toward the center of the rail, as viewed in Fig. 2. When the loop portion 14 is pressed against the 65 vertical face of the cross-tie 11 by longitudi-

nal movement of the rail, said pressure tends to tilt the jaw end of the anchor about its horizontal axis and in so doing increases the grip of the jaw end on the rail by exerting a pinching grip between the surfaces 18a and the surface 13a. It will also be seen in this connection that the pressure of the loop 14 against the cross tie exerts a pressure tending to move the angular portion 17 of the loop toward the vertical, that is to say, toward a vertical plane extending transversely of the rail. This pressure also exerts, in addition to the pinching grip, a spring grip vertically of the rail in much the same manner that the transverse flexing of the portion 17 produces during the application of the anchor to the rail.

While I have described my invention in connection with one specific embodiment, it will be obvious that various modifications in structure may be provided without departing from the spirit of the invention. It will be understood, therefore, that I contemplate all such modifications in structure and equivalents coming within the scope of the appended claims.

I claim:

1. A rail anchor comprising a body provided with means for clamping the opposite flanges of a rail and provided intermediate said clamping means with an open loop having substantially vertically disposed arms spaced from each other transversely of the rail to provide a recess for receiving the lower corner of the rail base during the initial applying movement of the anchor and adapted to be flexed both transversely and vertically of the rail during the applying movement of the anchor whereby the reflex of the loop exerts a spring grip on the rail.

2. A rail anchor comprising a body provided with a jaw at one end which extends over and bears against the top of one base flange, means at the other end for engagement with the other flange of said base, a depending tie abutment adapted to flex transversely of the rail and provided with a bracing arm extending upwardly and backwardly relative to the tie and bearing against the bottom of the rail at a point beneath said jaw.

3. A rail anchor comprising a body provided with a jaw at one end which extends over and bears against the top of one base flange, means at the other end for engagement with the other flange of said base, a tie abutment comprising a depending open loop the arms of which are spaced a part transversely of the rail adapted to flex transversely of the rail one of said arms providing a brace beneath the rail which extends upwardly and backwardly relative to the tie against which said abutment bears.

4. A rail anchor comprising a body portion formed at one end with a jaw for en-

gagement with the top surface of one base flange, and a tie abutment comprising a depending loop, one arm of which extends upwardly and backwardly relative to the cross tie against which said abutment bears, a forwardly extending portion at the upper end of said backwardly extending arm which bears against the bottom of the rail base, and means for gripping the other base flange.

5. A rail anchor comprising a body portion formed at one end with a jaw for engagement with the top surface of one base flange and a tie abutment comprising a depending loop, one arm of which is substantially perpendicular to the bottom surface of the rail and the other arm of which extends upwardly and backwardly relative to the cross tie against which said abutment bears, and a forwardly extending portion at the upper end of said backwardly extending arm which bears against the bottom of the rail base, and means for gripping the other flange of said rail base.

25. 6. A rail anchor comprising a body portion formed at one end with a jaw for engagement with the top surface of one base flange and a tie abutment comprising a depending loop, one arm of which extends upwardly and backwardly relative to the cross tie against which said abutment bears, a forwardly extending portion at the upper end of said backwardly extending arm which bears against the bottom of the rail base at a point below said jaw, and means for gripping the flange at the other side of said base.

7. A rail anchor comprising a body portion formed at one end with a jaw for engagement with the top surface of one base flange of a rail and a tie abutment comprising a depending loop, one arm of which extends substantially perpendicular to the bottom surface of the rail and the other arm of which extends upwardly and backwardly relative to the cross tie against which said abutment bears and also inclines outwardly toward the adjacent edge of the rail base, a forwardly extending portion at the upper end of said backwardly extending arm which bears against the bottom of the rail base at a point below said jaw, whereby flexing of said last mentioned arm transversely of the rail exerts a gripping force through said jaw and said forwardly extending bearing on the top and bottom respectively of the base flange.

8. A rail anchor comprising a body portion formed at one end with a jaw for engagement with the top surface of one base flange, and a tie abutment comprising a depending loop, one arm of which extends substantially perpendicular to the bottom surface of the rail base and bears against the vertical edge portion of one base flange of the rail, and the other arm of which extends

upwardly and backwardly relative to the cross tie against which said abutment bears, a forwardly extending portion at the upper end of said backwardly extending arm which bears against the bottom of the rail base, and means for gripping the other base flange of said rail.

9. A rail anchor comprising a body portion formed at one end with a jaw for engagement with the top surface of one base flange, and a tie abutment comprising a depending loop, one arm of which is substantially perpendicular to the bottom surface of the rail and the other arm of which extends upwardly and backwardly relative to the cross tie against which said abutment bears and also inclined outwardly toward the adjacent edge of the rail, a forwardly extending portion at the upper end of said backwardly extending arm which bears against the bottom of the rail base at a point below said jaw whereby movement of said last mentioned arm either transversely or longitudinally of the rail exerts a vertical gripping force on the top and bottom surface of the rail base flange engaged by said jaw, and means at the other end of said body adapted to be forced into gripping engagement with the other base flange of the rail.

10. A rail anchor comprising an under rail portion formed with means for engaging opposite edges of the rail base and formed intermediate said means with an open loop, the arms of which are adapted to be spread in application of said gripping means to the rail; said loop comprising a substantially vertical arm for engagement with an edge of the rail base and an arm extending upwardly and backwardly from a cross tie, the upper end of said backwardly extending arm providing a striking face against which force may be applied to spread said arms.

11. A rail anchor for resisting longitudinal movement of a rail comprising a body and means in the plane of the body for gripping opposite edges of the rail base, means yieldable transversely of the rail to permit engagement of the rail gripping means over opposite edges of the rail base, said yielding means being braced longitudinally of the rail so as to be non-yielding to forces exerted longitudinally of the rail.

12. A rail anchor for resisting longitudinal movement of a rail comprising rail gripping means at one end comprising a jaw for engagement with the top surface of one base flange, a depending loop adjacent said jaw providing a tie abutment and a bearing for engaging the bottom of the rail base, and provided at the other end with means for engagement with the other base flange; the said bottom bearing extending longitudinally of the rail beyond the plane of said jaw to resist tilting of flexing movements

of the said loop in a direction longitudinally of the rail.

13. A rail anchor for resisting longitudinal movement of a rail comprising rail gripping means at one end comprising a jaw for engagement with the top surface of one base flange, a depending loop adjacent said jaw providing a tie abutment and a bearing for engagement with the bottom of the base of the rail, and provided at the other end with means for engagement with the other base flange of the rail; the said loop being yieldable transversely of the rail to permit application of the device to the rail and the said bearing being positioned to extend a substantial distance backwardly from the plane of said jaw to provide a rigid grip of the jaw and bearing on the rail base during the presence of pressure on the anchor exerted longitudinally of the rail.

14. A rail anchor for resisting longitudinal movement of the rail comprising rail gripping means at one end including a jaw for engagement with the top surface of one base flange, and a depending loop adjacent said jaw providing a tie abutment and a bearing for engagement with the bottom of the base, and provided at the other end with means for engagement with the other base flange of the rail; the said loop being yieldable transversely of the rail to permit application of the anchor to the rail base, but a portion of said loop being inclined backwardly from the tie and bears against the base at a point rearwardly of said jaw to provide a rigid rail gripping engagement against forces exerted longitudinally of the rail.

15. A rail anchor for resisting longitudinal movement of the rail comprising a body and means in the plane of the body for engaging opposite flanges of a rail, a portion intermediate said gripping means yieldable transversely of the rail and inclined upwardly and backwardly to bear against the rail base beneath one of said means to provide a rigid grip on the rail to resist forces exerted longitudinally of the rail.

16. A rail anchor for resisting longitudinal movement of the rail comprising a body and means in the plane of the body for engaging opposite flanges of a rail, a loop intermediate said gripping means yieldable transversely of the rail and having a portion bearing against the bottom of the rail base at one side of the plane of said body to provide a rigid grip of the device on the rail against forces exerted longitudinally of the rail.

HAROLD G. WARR.
